COIN-SELECTING MECHANISM

Alfred Hakanson, North Arlington, N. J., assignor
to Peerless Weighing & Vending Machine Cor-
poration, Long Island City, N. Y., a corpora-
tion of Delaware

Application July 7, 1937, Serial No. 152,346

2 Claims. (Cl. 194—97)

The invention relates to novel and useful coin selecting mechanism to detect and prevent fraud in the use of coin-controlled machines and to insure operation of any coin-controlled device 5 only by the coin with which it is intended to function.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a front perspective view of the mechanism embodying the invention and showing a 25 coin in the actuating station;

Fig. 2 is a rear perspective of the mechanism shown in Fig. 1;

Fig. 3 is a front elevation of the mechanism with the lower portion of the movable front wing broken away to show the coin pathway;

Fig. 4 is a transverse vertical section on line 4—4 of Fig. 3;

Fig. 5 is a view similar to Fig. 4 but showing the elements moving into coin discharging position;

Fig. 6 is a transverse vertical section on line 6—6 of Fig. 3;

Fig. 7 is a fragmentary transverse vertical section on line 7—7 of Fig. 6;

Fig. 8 is a vertical section along the interior face of the actuating plunger looking in the same direction as Fig. 4 and showing the parts in their lowermost position or a position of rest;

Fig. 9 is a view similar to Fig. 8 but showing the parts approaching their uppermost position;

Fig. 10 is a fragmentary detailed side elevation of the mechanism showing the coin slot and coacting parts in coin-receiving position;

Fig. 11 is a view similar to Fig. 10 and showing the coin slot when the parts are in coin-discharging position;

Fig. 12 is a detail in perspective of the coin discharging interponent which coacts with the 55 coin in its actuating position;

Fig. 13 is a perspective detail of the scale or balance for testing coins as to weight;

Fig. 14 is a detail in perspective of the lower diameter gauge; and

Fig. 15 is a similar perspective of the upper 5 diameter gauge.

The invention is directed to providing a mechanism for selecting and cooperating with discs or coins of predetermined characteristics, while all other coins, discs and like objects which do not correspond to the predetermined standard in all particulars will be detected and rejected. The invention is particularly useful in connection with coin-controlled vending machines and other coin-controlled machines wherein a coin of 15 predetermined standards is utilized as an actuating or releasing means for effecting further operation of the machine. The invention is of wide general application and high utility in detecting and preventing use of slugs, counterfeit coins and other spurious articles.

One object of the invention is to provide a very compact, sturdy and simple coin-selecting mechanism which can be attached as a coin detector to practically any machine which operates on 25 the coin slot principle. Accordingly the mechanism of the invention combines within very small compass a great number and variety of coin-testing and selecting elements which are capacitated to very accurately and rapidly detect 30 and reject articles which deviate in any particular from the predetermined coin with which the machine is designed to coact. The mechanism not only provides means for testing and detecting 35 falsities and irregularities in coins, but also said testing means are selectively variable and controllable in their capacities whereby to calibrate the mechanism for operation with different types and denominations of coins and also to permit very nice setting of one or more of said testing 40 means to detect a relatively slight element of difference between a good coin and a bad one, as for example, where a certain imitation or slug is prevalent in a particular locality.

In general the mechanism comprises a coin 45 pathway operating on the principle of a gravity chute, along which the coin travels to reach an actuating station. In the chute and preferably projecting from the faces thereof are successively arranged various devices for testing the coin as to various features and for arresting any coin or other article which does not conform to the standard in the feature for which it is being tested by the particular device. A coin which successfully passes all of the testing devices 50 55

(hereinafter called a "good" coin) will arrive at a station whereat it cooperates to effectuate initial actuation of the vending machine or other coin-controlled elements with which the selecting mechanism is associated. After initiating actuation of the machine the coin is delivered to a strong box or other receptacle. Means are also provided for selectively returning the good coin from the actuating station to the operator as an alternative to actuating the machine. Any disc, slug, counterfeit coin or non-standard coin (hereinafter called "bad" coins) which has been arrested by the testing devices, and prevented from reaching the actuating station, is discarded by a preliminary movement of the machine actuator, whereby the coin testing and arresting devices are retracted from the coin pathway. To effect retraction of said testing devices means are provided for permitting a preliminary movement of the actuator mechanism which causes the retracting and discharging operation, regardless of whether or not a good coin is in the actuating station so that any attempt to actuate the machine with a bad coin causes the discharge thereof.

Among the testing devices which may be positioned in the coin pathway are a gauge for testing the thickness of coins; a gauge for testing the diameter; means for discovering and arresting discs with holes in them, such as washers; means for testing the weight of coins; means for detecting coins or discs having paramagnetic qualities, such as iron or steel slugs; and means for detecting coins of improper weight. All of these testing devices, and others if desired, are preferably arranged along a relatively short and simple gravity-chute pathway so as to interfere with and arrest the progress of any bad coin which fails to correspond to the standard for which the testing device is set. Bad coins so arrested are thus prevented from reaching the actuating station and are automatically discarded upon any attempt to operate the machine actuator.

It will be understood that the foregoing general description and the following detailed description as well are exemplary and explanatory of the invention but are not restrictive thereof.

Referring now in detail to the present preferred embodiment of the invention illustrated by way of example in the accompanying drawings, the coin-selecting and testing mechanism, illustrated as a whole in Figs. 1 and 3 comprises a main frame casting having a horizontal base 1, a vertical side wall 2, a horizontal top 3 and a vertical front wall or plate 4. The front wall or plate 4 constitutes the main vertical flat face of the coin pathway, along which the coin travels from its introduction into the coin slot until it arrives at the terminal actuating station. As herein-after described said main face 4 of the coin chute or pathway is provided with a plurality of openings through which the principal coin-testing devices extend and from which they are retractable to clear the face to discard bad coins which have been arrested thereby.

In accordance with the invention, the main vertical faces which determine the sides of the coin chute or pathway are relatively movable with respect to each other, being preferably separable to effect discharge of bad coins which have been arrested in the chute. As above described, one vertical face of the coin chute is fixed, being defined by the flat face 4 of the main casting, while the opposite flat face of the chute is

defined by the inner wall or face 6 of a vertically disposed plate or wing 5 which is pivotally suspended from the top 3 of the main casting to hang parallel to the face 4. Hinged suspension of the pivotal chute, plate or wing 5 from the top 3 of the main frame is provided by a pin 10 which is suitably journaled in the reduced front portion of the top 3 and in conforming side arms 11 of the wing 5. As will be clear from Figs. 3 to 6, the faces 4 and 6 form between them a narrow vertical space or chute along which the coin may travel with the faces of the coin parallel to said faces 4 and 6. The spacing between faces 4 and 6 is effected by a raised portion 12 along the upper part of plate 4 and is somewhat greater than the maximum thickness of any coin to be used. As shown in Fig. 3 the raised portion 12 terminates in an edge 13 which inclines inwardly and downwardly from the side wall 2, curving into the vertical, to form the upper and inner edge of the coin chute. The mouth or entrance slot to the coin chute lies near the top of the side wall 2, the upper edge of the slot being determined by the narrow end of the raised portion 12. The corresponding upper portion of the pivotal wing 5 is cut away at 15 to form one side and the bottom edge of the slot and, as shown in Figs. 10 and 11, a U-shaped guard plate 16 is preferably attached to the wing 5 and overlies wall 2 to outline the bottom and vertical sides of the coin slot.

The invention provides for free passage of a good coin from the entrance slot to a terminal station, and the pathway along which said coin travels is provided with a plurality of testing devices or gauges which permit travel of the good coin but arrest any coin which does not conform to the standard required by any gauge. As embodied, the first of such gauges is one for testing the thickness of coins, although, of course, the particular order and arrangement of the gauging or testing devices is largely optional. As shown, the thickness gauge comprises a stud 20 which is threaded into a suitable bore 21 in the wing plate 5, the latter being thickened at 22 for that purpose. The inner end 20 of the stud is positioned to extend into the coin pathway and limit the effective thickness of the coin chute so as to arrest any coin which is too thick. For example, if the device is set to operate upon a one-cent piece, the position of the inner end of the stud 20 will be such as to just permit passage of a one-cent piece but prevent passage of any thicker coin such as a nickel or a quarter. As shown, the thickness gauge is variable to calibrate the device for other coins, the threaded stud having a nut 23 to set the stud at the desired point.

The invention provides means for guarding against attempts to recover a coin after it has been dropped into the slot and entered the actuating station, as might be tried by a wire, thread or the like attached to the coin or pushed into the coin pathway after the coin has entered. As embodied, the wing plate 5 is provided with a guard comprising a plate 25 which is pivotally mounted on a horizontal pin 26 journaled at its ends in the upturned side walls 27 of the wing plate 5. The upper portion of plate 25 is relatively short and is provided with an inwardly disposed horizontal lip 28 which projects into a corresponding horizontal slot 29 in the plate 5, but normally does not extend through said slot and into the inner face 6 of the wing plate 5 because of the counter-balancing effect of the lower and

longer portion of said plate 25. Said lower portion of member 25 is bifurcated to form two downwardly and inwardly extending tongues 30 which extend below and beyond the inner end of plate 5 and into cooperating openings 31 and 32 in the main plate 4. The weight and balance of the parts of the guard member 25 is such that the tongues 30 normally extend into the openings 31 and 32 and thus lie across the coin pathway. When a coin reaches the tongues 30 it causes the plate 25 to tilt outward permitting the coin to travel past the tongues, whereupon the tongues return into the openings. When a coin C has arrived at the terminal station, as shown in Fig. 3, efforts to withdraw it therefrom will be blocked by the tongues 30. Furthermore, any attempt to introduce into the coin pathway a retracting device such as a wire hook will be blocked by the plate 25, the tongue 28 thereof binding the upper portion of the wire and the coin against return movement when the tongues 30 are retracted, and vice versa.

Plate 25 also prevents the introduction of a large number of coins into the device at one time, thereby preventing an operator forcing a bad coin into the actuating station by pushing on a column of coins lined up in the coin passageway. With a coin in the actuating station, if a second coin lies against the tongues 30, the upper lip 28 of the plate 25 will close the passageway above, so that no more coins can be forced into the lower part of the passageway and thus bear against a coin in the actuating station. In this way it is impossible for the operator to build up a column of coins extending through the passageway against which he could exert pressure by forcing a new coin into the coin slot.

Means are provided for arresting coins in the coin pathway which exceed the diameter of a good coin. As embodied, a horizontal slot 35 is provided in the face plate 4 and through said slot extends a stud 36, which projects beyond the face 4 to terminate just short of the inner face 6 of the wing 5. The stud 36 thus provides on the far or inner side of the coin passageway a bar against coins of excess diameter. Means opposite said stud 36 for cooperation with it to gauge the coin diameter comprise a plate 40 which is pivotally connected at 41 to the inner face of arm 27 of the swinging chute plate 5 and forms the rear edge of the coin chute. Said plate 40 is trapezoidal in outline and lies across the inside face of vertical plate 2 of the main frame, being adapted to pass through a vertical slot 42 therein. The plate 40, shown in normal position in Figs. 6 and 10, is provided with an L-shaped edge 43 which normally lies vertically along one side of the coin slot to permit entrance of the coin. The inner face 44 of the plate 40 forms a gauge or boundary for one edge of the coin while its opposite edge passes the diameter gauge stud 36 in traveling downward. A coin of excess diameter will thus be suspended between the stud 36 and the surface 44 of plate 40. The elongated slot 35 permits variations in the position of the stud 36 for coins of different diameters. The means for supporting and for varying the position of stud 36 will be hereinafter described.

The invention provides means for detecting and arresting objects, such as washers or nuts having holes in them and as embodied, said means are positioned next in sequence in the coin passageway. As shown, a vertical slot 50 is provided in plate 4, said slot being located substantially intermediate the diameter stud 36 and the gauge

plate 40. A rotatable pronged disc 51 is rotatably mounted on a horizontal threaded shaft 52. Said disc is of irregular form and is provided with a prong 53 which normally extends outwardly through the opening 50 and into the coin passageway, being held lightly in that position by gravity. The major weight of the disc 51 is on the opposite side of shaft 52 and so tends to rotate the disc clockwise (Fig. 6) but is prevented from moving it farther in that sense by the lower triangular point 54 of the disc which contacts with the bottom of opening 50'. Disc 51 is capable of a limited rotational movement about shaft 52 in a counter-clockwise direction whereby prong 53 may rock downwardly from its normal horizontal position until it contacts the bottom surface of the opening 50. Further downward movement of prong 53 in a counter-clockwise direction is also prevented by the substantially opposite prong 55 which is so long that it strikes above the top of opening 50. An intermediate prong 57, preferably slightly hook-shaped, extends from the disc 51 and is adapted to swing through the opening 50 and project from the face of plate 4 when the prong 53 is depressed. Thus when a disc having a central opening, such as a washer, is attempted to be passed through the coin passageway its bottom edge will temporarily depress the prong 53 of disc 51, but as the central opening of the washer comes abreast of the opening 50, the prong 57 projects and hooks into the washer opening to catch and hold the washer. It will be noted that the disc 51 and the opening 50 are substantially midway between the diameter gauge members 36 and 44, so that the central portion of a disc is automatically caused to pass across the opening 50. Thus common articles such as washers having holes at their centers will be positioned for engagement by the prongs of disc 51 in traveling down the coin passageway. The disc 51 is interiorly threaded so that it may be variably positioned along threaded shaft 52 to center the prong 57 for discs of different diameters.

The invention provides means for detecting and arresting discs, counterfeit coins or other spurious objects having paramagnetic qualities, as an iron washer for example. As embodied, a permanent magnet, preferably of the horse shoe type, is mounted so that its poles 60 and 61 lie across the coin passage, preferably just below the opening 50 in plate 4. The magnetic poles extend through suitable openings 62 and 63 in the face plate 4 and in their normal position lie substantially flush with the face 4. The openings 62 and 63 are preferably made substantially larger in diameter than the magnet poles to provide for free retracting movement, which is accomplished as hereinafter described.

The invention also provides means for detecting and arresting discs which are lighter in weight than the standard good coin, said means preferably coacting with a second diameter-controlling means. As embodied, an inclined, depressible ledge 65 (Figs. 3, 6 and 13) is mounted below the magnet poles 60 and 61 to form the inclined bottom of the coin passageway. Said ledge projects through a triangular opening 66 near the bottom of the face plate 4 and is inclined downwardly and toward the right (Fig. 3) to cause coins falling thereon to roll in the direction of its inclination. The ledge 65 is tilted rearwardly, its outer edge or lip being higher, so that coins tend to bear against the face plate 4.

The ledge 65 constitutes one end of a weighted

lever or balance 67 which extends through the opening 66 and is pivotally mounted in the rear of plate 4 on a horizontal axle 68, (Fig. 13). The portion of lever 67 to the rear of axle 68 is enlarged and provided with a threaded socket 69 in which is seated a threaded bolt 70. One or more nuts 71 are threaded on to said bolt 70 so that the balance of lever 67 may be nicely varied by the positioning of the nuts 71 along the bolt. 10 The balance of the lever 67 is so adjusted as to normally hold the upper inclined face 72 of the lever 67 against the correspondingly inclined upper edge of the opening 66 in plate 4.

Means are provided for requiring the ledge 65 to be depressed a predetermined amount by the weight of a coin resting thereon in order for the coin to be released for further travel along the passageway. As embodied, a second diameter-gauge stud 75 is mounted above the ledge 65, 15 projecting through an inclined slot 76 in the face plate 4. Stud 75 is so positioned in slot 76 that the distance between the lower surface of the stud and the upper or left hand corner of ledge 65 is less than the diameter of a standard good coin when the ledge 65 is in its upper or undepressed position. However, when a coin of standard weight rides onto ledge 65, it will depress the ledge sufficiently to permit a coin of the standard diameter to roll past the bottom of stud 20 75. A coin of the standard diameter but too light in weight will not depress the ledge sufficiently and will be stopped from further travel by the stud 75.

Having passed the weight testing gauge provided by the ledge 65 of lever 67, the good coin is enabled to travel to the terminal station. As embodied said station comprises devices for temporarily holding the coin in a position where it will cooperate to effect operation of the actuating devices of the machine for which the coin is supplied. The coin is held in said actuating station until the actuating movement has been substantially advanced, and is then discharged into a suitable receptacle during the 40 final portion of the actuating movement. In accordance therewith an inclined coin-supporting ledge 80 is positioned in the coin passageway just beyond the lower end of the inclined weighing ledge 65, so that the good coin will roll onto said ledge 80. The ledge 80 extends from the face plate 4 which has a rectangular cut-out portion 81 at that point. The ledge 80 constitutes an inclined tongue projecting from a cylindrical member 82 (Fig. 12), the periphery of which is substantially tangential with face plate 4. Cylindrical member 82 is mounted for limited pivotal movement with respect to face plate 4, being provided with an axially extending shaft 83 which is journaled in the enlarged bottom portion 84 of the main casting, slightly to the rear of the rear face of the main vertical plate 4.

Means are provided for arresting the good coin so that it rests upon the ledge 80 for the purpose of holding it there for the actuating operation. 65 As embodied, an inclined coin-restraining edge 85 is mounted above and slightly beyond the ledge 80 so that the upper part of the coin edge will lie thereagainst when the ledge 80 is in its normal position, the distance between inclined edge 85 and the inclined ledge 80 being slightly less than the diameter of the good coin. Coin-restraining edge 85 is formed in an angled block 86 which lies against the face 4 and the right-hand side edge 90 thereof. The block 86 is supported at the proper height by a binding screw 70 75

87 which passes through a suitable vertical slot 88 in the block and is seated in a threaded recess tapped in the face plate 4. If desired, a coin-discharge guide plate 89 may be formed on the outer face of block 86, the lower portion of said 5 plate extending downwardly and outwardly from the block to aid in the discharge of the coin as will hereinafter appear. Thus it will be clear that the coin in its terminal station is held between the inclined ledge 80 and the inclined 10 edge 85.

It will be clear that a coin which is too small in diameter will not be retained in the actuating station, even though it succeeds in reaching said station. For example, if the mechanism is calibrated to operate on a nickel, a one cent piece will not be arrested at the ledge 80, but will escape the restraining edge 85 and roll on to return to the operator through the chute 159.

Referring now to the machine-actuating means 20 with which the coin is designed to cooperate when in the terminal actuating station, the invention as shown is provided with a vertically movable plunger 95 which may be connected by any suitable linkage (not shown) with mechanism of a machine to be controlled or actuated or released thereby. In a vending machine for example, the vertical plunger 95 may be connected to control the release of article dispensing devices, as shown for example in my copending 25 application Ser. No. 152,347, filed as of even date herewith. It will be understood, however, that the invention is not limited to any particular application or use of the actuating mechanism which is put in operation by the presence of the 30 good coin, and so far as the present invention is concerned said actuating mechanism may be combined with any other device which may be susceptible of control by proper connection with said actuating means.

As embodied, the actuating plunger 95 is operatively connected to elevate a vertically movable frame 98 which is adapted to travel upwardly along the inner or right hand side of Figs. 1 and 3 of the mechanism, that is, the side 40 opposite the coin slot entrance. The plunger 95 is suspended in the lower end block 99 of the frame 98 (Figs. 8 and 9) which is bored at 101 to loosely receive the plunger. The plunger is adapted to have a limited idle movement with respect to the block 99 so as to permit some vertical manipulation of the plunger without any actuation of the mechanism. Accordingly a kerf 100 is cut in the plunger a short distance below the upper end thereof, the plunger ordinarily being loosely suspended in the bore 101 of the block 99 by the shoulder 102 of the kerf which rests against the inner end of a threaded supporting stud 103 which extends for a short distance into the bore. At the limit of its upward idle stroke, the upper end of the plunger 95 is adapted to contact with and push against a shoulder 104 formed in the frame 98.

Upward movement of the frame 98 is opposed by a helical compression spring 106 which at its upper end is fixed to an arm 107 forming part of the top plate 3 of the main frame. Said spring 106 is mounted around a guide rod 108 which is fixed to and extends downwardly from the end of arm 107. The upper portion of vertical frame 98 is enlarged at 109 to provide a vertical cylindrical recess 110 in which the lower end of the helical spring 106 is seated and into which the rod 108 is adapted to travel. Thus upon upward movement of the vertical frame 98 helical 70 75 80 85 90 95 100 105 110 115 120 125 130 135 140 145 150 155 160 165 170 175 180 185 190 195 200 205 210 215 220 225 230 235 240 245 250 spring 106 is compressed and the cylindrical recess 110 travels up and around the spring and its confined guide rod 108.

A limited upward movement of the vertical frame 98 is permitted, regardless of whether or not a good coin is in the terminal actuating station, but means are provided for preventing a full upward stroke of said vertical frame except when a good coin is in said station. As embodied, said preventing means constitute an interponent which is formed as an integral part of the cylindrical member 82. As shown in Figs. 8, 9 and 12, said cylindrical member 82 is provided with an upwardly extending arm 115 which at its upper end is provided with horizontally extending shoulder 116 having a flat underface 117. The rear face 118 of said shoulder 116 is also flat in the vertical plane. Shoulder 116 comprises an interponent which is adapted to move into position to block the upward travel of vertical frame 98 unless a coin is in the actuating station, the presence of the coin preventing such blocking movement of the interponent 116. The blocking movement of the interponent is effected by a rearward rocking of the arm 115 of cylindrical member 82, by means of a helical spring 120 which lies about a stud 121 which is fixed to the rear face of main plate 4. The rear end of the spring 120 is seated in a cooperating recess 122 in the arm 115, so that the spring tends to rock the member 82 and arm 115 rearwardly (counterclockwise in Figs. 4, 5, 8 and 9) unless a coin C is in the terminal station. If the coin C is in said station, as shown in Figs. 4 and 8, it lies between the ledge 80 and the edge 85 and prevents upward, i. e., counterclockwise movement thereof.

The vertical frame 98 is designed to cooperate with the interponent 116 to engage therewith to block further upward movement of the frame, or to clear the interponent and permit such further upward movement, depending on whether a coin is in the terminal station. As shown, an L-shaped block 125 is fixed to and extends from the inner side of the vertical frame 98. The block 125 is so positioned that its flat vertical face 126 will just clear the rear flat face 118 of the interponent 116 (Fig. 9) when the coin is in the terminal station. Consequently the vertical frame 98 can travel upwardly for its full stroke when and only when a good coin C is in the terminal actuating station.

However, when the coin is not in said station and the interponent 116 is free to rock under the influence of spring 120, the lower face 117 of the interponent will move into the path of block 125. Accordingly, upon preliminary upward movement of the vertical frame 98, the upper inclined face 127 of block 125 will come into contact with lower face 117 of the interponent and further upward movement of the vertical frame 98 will be prevented.

In accordance with the invention, means are provided for effecting delivery of the coin from the terminal actuating station during the final portion of the upward stroke of the vertical frame 98. As embodied, an L-shaped coin ejecting lever 130 is pivotally connected by its upper arm 131 to the vertical frame 98 at 132. As shown in Fig. 8, the lower arm 130 of the coin ejecting lever normally lies retracted below and behind the terminal coin station, but is adapted upon full upward stroke of the plunger to rise upwardly and forwardly (Fig. 9) to lift and push the coin off the ledge 80 whence it falls to delivery into a suitable receptacle as hereinafter

described. The embodied means for effecting said upward and outward movement of the coin discharge lever comprises an outwardly and rearwardly sliding cam slot 135 which is formed in a wing member 136 extending rearwardly from the main plate 4. The upper portion of arm 131 of the coin discharge lever is provided with a pin 137 which lies at right angles to the end of the lever and is adapted to travel in the cam slot 135. Thus upon the preliminary upward movement of the vertical frame 98, the coin ejecting lever is retained in its retracted position, but upon further upward movement the inclined part of the cam slot causes the arm 130 to move outwardly and upwardly to eject a coin. As shown in Fig. 9, the inclined portion of the coin guard plate 89 causes the ejected coin to be deflected downwardly for ultimate deposit.

In accordance with the main features of the invention the ejected good coin may be deposited in any suitable receptacle and the particular receptacle shown is no necessary part of the invention. As shown, the coin selecting mechanism as a whole is mounted upon the top of a strongbox 140, the top portions thereof being inclined as shown at 141. A trap door 142 is pivotally mounted in the upper part of the inclined box top 141, having a side flange 143 which is journaled on a fixed axle 144. Means are provided for causing the trap door to positively open to permit entrance of a good coin and to be positively closed upon return stroke of the vertical frame. As shown, an actuating tongue 145 is mounted to extend forwardly from the bottom block 99 of the vertical actuator frame. The side flange 143 of the trap door is notched at 146 to cooperate with said tongue 145. The upper inclined edge 147 of the notch is spaced above the upper surface of tongue 145 far enough to permit the preliminary upward movement thereof without affecting the trap door. When the vertical frame goes into its extended upward movement, that is, when a good coin is in the terminal actuating station, then the tongue 145 is adapted to engage the edge 147 and rock the trap door to its open, coin-receiving position, as shown in Fig. 5. Upon the return movement of the vertical frame, the lower inclined edge of the tongue 145 engages the similarly inclined lower edge 148 of the notch 147 and returns the trap door to the closed position as shown in Fig. 4.

The invention provides means for permitting only a single actuating stroke of the vertical plunger 95, even though the vertical frame 98 and its cooperating parts may be sustained in the uppermost position. As shown, a supplementary weighted lever 300 is pivotally suspended from the pivot 132 on the vertical frame so that it normally hangs behind the path of the plunger 95, being held in that position by a pin 301 which projects from the outer face of ejecting lever 130 and bears against the upper end of lever 300. However, when the vertical frame is supported in its uppermost position by pressure on the bottom block 99, the idle plunger 95, having dropped below the contact surface 104, lever 300 will then swing by gravity over the top of block 99. Thereafter upward movement of plunger 95 will cause its upper end to contact the bottom of lever 300 and thus prevent a second upward movement of said plunger. Thus only one effective upward stroke of the plunger 95 may be had through actuation by a single coin, even though the operator could succeed in forcing the vertical frame 98 and its connecting parts to stay in the upper- 75

most position. The mechanism described thereby prevents unpaid operations of the dispensing machine or the like which might otherwise be attempted by a dishonest operator.

5 In accordance with one feature of the invention, optionally operable means are provided for enabling the operator to effect return to him of the good coin after it has reached the terminal actuating station, instead of depositing it in the 10 strongbox and without any movement of the vertical plunger and frame. As embodied, said means comprise a manually operable device for downwardly and outwardly tilting the coin-supporting ledge 80 independently of the vertical 15 frame and while the latter is in its lowermost position. For this purpose the arm 115 of the cylindrical member 82 is provided with a rearwardly extending boss 150 (Figs. 2 and 12). Manual means for effecting an upward tilting 20 movement against the bottom of the boss comprise a lever 151 pivotally mounted at 152 and adapted to be actuated by horizontal movement of a pin 153. Such movement is given to the pin by means of a manually operable plunger 154 25 which has reciprocatory movement in a cylindrical bore 155 formed near the bottom of the main frame, the end of the plunger protruding from the side face 2 of the main frame. The bore 155 is slotted at 156 to receive and coat 30 with the inner part of the pin 153 and is adapted to be returned after actuation by a helical spring 157 which lies between the inner end of the plunger and the inner end of the bore 155. It will be clear that pushing in the end of the 35 plunger 154 will cause pin 153 and lever 151 to raise the boss 150 thereby depressing ledge 80 and causing the coin to roll along the ledge below the restraining edge 85. The coin then falls into a return chute 159 and thence back to the operator. 40

In accordance with the invention means are provided for retracting the bad coin detecting and arresting devices from the coin passageway so as to release and discard bad coins. As embodied, substantially all of said detecting and arresting devices are movably supported with respect to the fixed face 4 of the coin chute, so that upon preliminary upward movement of the vertical actuating frame 98, all of said devices 50 will be simultaneously retracted from the coin pathway, thereby to cause the bad coins to fall to discard. Accordingly, a wing member 170 is pivotally suspended in the rear of the main wall 4, being hinged at its upper end by pin 171 which is 55 journaled in the side frame members of the wing 170 and extends through a suitable cooperating bore in the top 3 of the main frame. In its normal or closed position, the wing member 170 hangs vertically and substantially parallel of 60 the rear face of the main plate 4 of the coin chute. Except for the thickness gauge stud 20, substantially all of the coin detecting and arresting devices hereinbefore described are mounted on and adapted to swing with the pivotally suspended wing plate 170. Thus the diametral gauge stud 36 extends from a slotted plate 175 which is adjustably mounted by a threaded bolt 175' seated in the rear face of wing member 170. Similarly the lower diameter gauge stud 70 75 projects from the lower end of an arm 176 which is vertically slotted at 177 in its upper end and is adjustably mounted in the rear face of the wing 170 by a bolt 178.

The threaded shaft 52 which supports the washer-catching disc 51 is also horizontally sup-

ported in wing plate 170 which is thickened at 180 for that purpose. The plate is suitably slotted at 181 to permit the disc to extend therethrough, said slot being aligned with opening 50 in the main plate 4. Similar cooperating openings 183 and 184 are provided in the wing plate 170 for admission of the gauges 36 and 75 respectively. 5

The horseshoe magnet 185, the poles of which have been already described, is supported against 10 the rear of wing plate 170 for ready removal and replacement by means of a bar 186 held in place by threaded bolt 187, the poles of the magnet being curved to project through suitable openings in the wing plate 170 and thence through the 15 openings 62 and 63 of plate 4, as previously described.

The weight gauge 67 is also pivotally supported in the wing plate 170, the axle 68 thereof being journaled in the enlarged portions 180 of 20 the wing plate 170, the latter also being provided with a suitable opening 181 for extension of the lever 67 therethrough and through the openings 66 in the main plate 4.

Referring now to the embodied means for im- 25 parting a rearward swinging movement to the plate 170 to effect retraction of the coin arrest- 30 ing devices, a block 196 is provided at the upper end of the vertical frame 98 and a cam track 198 is formed therein for cooperating with an 35 actuating pin 197 which extends from the side wall of the plate 170. As will be clear from the 40 shape of the cam, initial upward movement of the vertical frame will immediately cause the plate 170 to swing outwardly and thus to retract the several coin-testing and arresting devices 45 from the face of plate 4.

The front wing plate 5 is also adapted to swing 50 outwardly and away from the face plate 4 simultaneously with the similar and opposite move- 40 ment of the wing plate 170. For this purpose the enlarged portion 195 of the vertical frame 98 is 55 provided with another cam track 199 in which travels a pin 200 attached to the swinging plate 5. The outward swinging of plate 5 by means 45 of said cam track 199 causes an initial separation of the faces of the coin chute and thus causes any bad coin, which had been arrested by any 50 of the testing devices, to immediately drop from the chute and onto the spillway 141 whence it passes to discard.

Referring now to Figs. 10 and 11, means are 55 provided for blocking the coin slot against introduction of coins during any actuation of the vertical frame 98. As shown, the outward swing- 60 ing of swing plate 5 carries with it the gauge plate 40 which then covers and blocks the coin slot from the inside, being provided with a suitable slot 205 in its lower end, which cooperates with a pin 206 in the main side plate 2. 65

The invention in its broader aspects is not limited to the specific mechanisms shown and described but departures may be made therefrom within the scope of the accompanying claims 70 without departing from the principles of the invention and without sacrificing its chief advantages. 75

What I claim is:

1. A coin-selecting mechanism including in 70 combination a coin chute having one face formed by a fixed vertical plate, the opposite face being formed by a member normally lying parallel to the fixed face, but being pivotally suspended for swinging movement away from said fixed face, testing means on said member extending across 75

the coin chute and into an opening in the fixed plate, a second pivotally movable member on the other side of the fixed plate, a plurality of bad-coin arresting devices mounted on said second pivotal member and projecting therefrom through openings in the fixed plate and into the coin chute, and means for simultaneously swinging both said pivotal members in opposite directions away from the fixed plate to clear the coin chute of bad coins.

2. A coin-selecting mechanism including in combination a coin chute having one face formed by a fixed vertical plate, the opposite face being formed by a member normally lying parallel to the fixed face, but being pivotally suspended for swinging movement away from said fixed face,

a coin engaging device pivotally mounted on said member and normally extending therefrom through an opening in the fixed plate, a second pivotally movable member on the other side of the fixed plate, a plurality of bad-coin arresting devices mounted on said second pivotal member and projecting therefrom through openings in the fixed plate and into the coin chute, means for simultaneously swinging both said pivotal members in opposite directions away from the fixed plate to clear the coin chute of bad coins, a station on said fixed plate for receiving a good coin, and means for holding the good coin in said station during the swinging movement of said members.
